UNITED STATES PATENT OFFICE

2,388,334

COMBINATION VALVE NOZZLE

William H. Leinweber, Chicago, Ill.

Application January 15, 1944, Serial No. 518,360

1 Claim. (Cl. 299—138)

This invention relates to certain new and useful improvements in a combination valve nozzle and more particularly to a combined valve and nozzle of the sleeve type construction. The invention has for one of its objects the provision of an improved construction of this character which will be highly efficient in use and economical in manufacture.

Among the several objects of the invention is the provision of a combination valve and nozzle of the character hereinafter described in which a great spread of water will result with a finer spray of predetermined lengths in a straight line.

A still further object of the invention resides in the fact that the valve and nozzle embodying this invention is capable of a variety of uses.

Another object of the invention is the novel manner of closing and opening the water ports of the nozzle.

Other objects will appear hereinafter.

The invention consists in the novel combination and arrangements of parts to be hereinafter described and claimed.

The invention will be best understood by reference to the accompanying drawing showing the preferred form of construction, and in which:

Fig. 1 is a side view of the invention;

Fig. 2 is a sectional detail view taken substantially on line 2—2 of Fig. 1; and

Fig. 3 is a longitudinal sectional detail view of the invention.

In the drawing I have illustrated the preferred form of construction of the invention by which the several objects of the invention are attained.

In this connection the nozzle embodying my invention is indicated at 10. This valve includes an outer sleeve 11. Formed in this sleeve 11 at a predetermined point is an outlet in the form of an elongated slot 12.

The opposite ends of this sleeve 11 are closed by caps 13 and 14. The cap 14 has formed thereon a boss 15. Threaded upon this boss 15 is a bushing 16 within which is a felt or rubber washer 17.

Journalled through the boss 15 and the bushing 16 is a stem 18. The exterior of this stem carries a handle or knob 19.

The interior end of the stem 18 is secured in any suitable manner to the end wall 20 of a cylinder 21. Both ends of the cylinder are closed, one by the wall 20 and the other end by a plug 22. This closed cylinder is adapted to rotate within the sleeve 11.

In the cylindrical wall of this cylinder are 55

formed a plurality of spaced slots 23, 24 and 25. Each of these slots is adapted to register with the outlet 12. The longest of the slots is preferably equal to the length of the outlet 12.

Carried by the sleeve 11 is a nipple 26 to which the end of a hose or other supply line is connected. The interior end of this nipple projects through a cutout portion 27 of the cylinder 21. The end of this nipple 26 is closed as at 28. Formed in the side walls of the nipple 26, within the cylinder 21 are outlet ports 28.

In addition to the slots 23, 24 and 25 and the outlet slot 12 there may be formed in the walls of the cylinder 21 and sleeve 11 circular openings 29 which register when the slots 23, 24 and 25 are out of registration with the slot 12.

By rotating the cylinder 21 the slots 23, 24 and 25 may each be brought into registration with the slot 12 to vary the length and spread out the fineness of the spray. In this way the area to be covered may be controlled by the operator.

If desirable, in sprinkling lawns or in association of my nozzle with a fire extinguisher system, the same may be mounted in a well-known manner upon a whirling bracket or the like.

The simplicity of construction is at once apparent from the description herein.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

40 A combination nozzle and valve comprising a sleeve having an elongated slot formed therein, caps closing the ends of the sleeve, a cylinder having closed ends arranged for rotation in the sleeve and having a plurality of spaced slots formed therein each adapted to register with the slot of said sleeve, a handle, means for connecting the handle to the cylinder to facilitate rotating the latter, means for delivering a fluid to said cylinder, said means comprising a nozzle carried by the sleeve and having an end projecting through an elongated slot formed in the cylinder and having said end provided with opposite outlet ports.
